UNITED STATES PATENT OFFICE.

OSCAR J. HOLMES, OF ST. LOUIS, MISSOURI.

FIRE APPARATUS FOR OIL-TANKS.

1,142,520.

Specification of Letters Patent. Patented June 8, 1915.

Application filed September 2, 1913. Serial No. 787,735.

To all whom it may concern:

Be it known that I, OSCAR J. HOLMES, a citizen of the United States, and resident of St. Louis, Missouri, have invented certain new and useful Improvements in Fire Apparatus for Oil-Tanks, of which the following is a specification containing a full, clear, and exact description, reference being had to the accompanying drawings, forming a part hereof.

My invention relates to improvements in fire apparatus for oil tanks, and the object of my invention is to construct a fire apparatus especially designed for use in connection with oil tanks, which comprises a cover for the oil which will rise and fall with the oil and is arranged to at all times expose a minimum of oil surface, and further constructed so that there will be a minimum of space between the cover and the oil surface in order to minimize the generation of gases, and associated with such a cover is a plurality of extinguishers which will rise and fall with the oil and are so arranged that they will be thermally operated.

With the above purposes in view my invention consists in certain novel features of construction and arrangement of parts as will be hereinafter more fully described, pointed out in the claims and illustrated by the accompanying drawings, in which—

Figure 1 shows in elevation a fragment of a tank equipped with my improved fire apparatus; Fig. 2 is a sectional plan of an oil tank showing the relative arrangement of the fire extinguisher and the internal braces of the tank; Fig. 3 is a plan of one of the elements of my improved cover; Fig. 4 is a sectional elevation of one of the elements of the cover; Fig. 5 is a detail elevation partly in section showing one of the extinguishers employed in my apparatus; and Fig. 6 is a plan of the extinguisher shown in Fig. 5.

Referring by numerals to the accompanying drawings: 7 designates the oil tank having internal bracing structure 8.

9 and 10 designate fire extinguishers each of which is arranged to float in the body of oil and each of the types shown is arranged to contain a frangible bottle 11 provided with a gravity-actuated means 12 for breaking the bottle. Each of the gravity-actuated means is normally held elevated by means of a fusible link 13. In the one

form of extinguisher designated 9 there are eyes 14 secured to the extinguisher arranged to ride over guide rods 15 extended vertically throughout the height of the tank. In the form designated 10 there is a rope 16 extended over direction pulleys 17 to the exterior of the tank and each rope carries at its outer end a balancing weight 18. These extinguishers are arranged in such manner relative to the bracing structure 8 that they may move without coming in contact with the braces, as clearly shown in Fig. 2.

19 designates the floating cover for the oil. This cover is preferably made up of a plurality of hollow bodies 20 convexo-convex in cross section provided with annular flanges 21.

Each of the fire extinguishers is provided with a tube 22 in communication with the interior of the extinguisher and extending to and terminating in a cap 23 provided with a plurality of radially arranged nozzles 24.

In the practical operation of my improved apparatus, assuming the elements of the apparatus to be set for use as described, it is obvious that by reason of the buoyancy of the extinguishers as well as the cover, the extinguishers and cover will always be in their most efficient positions.

By reason of the fixed guides for both forms of extinguishers it is obvious that they may rise and fall without coming in contact with the bracing structure within the tank and, by reason of the cover being made up of a plurality of hollow bodies, it is obvious that the cover as a whole may rise and lower above and below said bracing structures and be in operative or efficient condition after having passed the bracing structure.

In the event of fire in the upper portion of the tank the fusible link 13 will melt and permit the gravity-actuated means 12 to break the bottle 11, thereby setting the extinguisher in operation.

The form of extinguishers designated as 9 will discharge their fire extinguishing gases into the zone next adjacent the surface of the oil, while the form of extinguishers designated 10 will discharge their gases into the zone next adjacent the surface of the oil for a limited period of time only when, due to the releasing of the contents of the extinguishers and the consequent loss of

2
weight, the balance weight 18 connected therewith will cause the extinguishers to be drawn upwardly toward the top of the tank, thereby discharging the fire extinguishing 5 gases throughout the tank to extinguish the bracing structures which are usually made of wood. By this arrangement it is obvious that the cover is of such nature to at all 10 times expose a minimum of oil surface and that the extinguishers have sufficient capacity and are of such nature as to automatically extinguish the fires in the tank above the oil surface.

I claim:

15 1. In a fire apparatus for oil tanks, a plurality of buoyant fire extinguishers, a thermally controlled discharge for the contents of each extinguisher, and a counterbalance for certain of the extinguishers, whereby 20 certain of the extinguishers will discharge their contents, when thermally released, into the vicinity of the oil surface, and other ex-

tinguishers will be elevated by the counter-balances as their contents are discharged.

2. In a fire apparatus for oil tanks, a 25 buoyant cover for the oil for the purpose of minimizing the gasifying of the oil, a buoyant fire extinguisher, arranged to rise and fall as the level of the oil varies, a thermally controlled discharge for the contents 30 of the extinguisher, arranged in the immediate vicinity of and above said cover, and a second like constructed extinguisher having a counterbalance arranged to cause the extinguisher to rise in the tank as its contents 35 are discharged.

In testimony whereof, I have signed my name to this specification, in presence of two subscribing witnesses.

OSCAR J. HOLMES.
